UNITED STATES PATENT OFFICE.

JOSEPH T. PELCHAT, OF BRADFORD, RHODE ISLAND.

RAILROAD-TIE.

1,331,670.

Specification of Letters Patent. Patented Feb. 24, 1920.

Application filed August 29, 1919. Serial No. 320,637.

To all whom it may concern:

Be it known that I, JOSEPH T. PELCHAT, a citizen of the United States, residing at Bradford, in the county of Washington and 5 State of Rhode Island, have invented certain new and useful Improvements in Railroad-Ties, of which the following is a specification.

My invention relates to railroad ties and 10 to the means for fastening the rails thereon.

The essential objects of my invention are to securely maintain the rails to the tie; to prevent the lateral spread of the rail base flanges, web, and head; to furnish adequate 15 support; to afford facile assemblage of the parts; and to attain these ends in a strong, permanent, and inexpensive structure.

To the above ends essentially, my invention consists in such parts and in such combinations of parts as fall within the scope 20 of the appended claims.

In the accompanying drawings which form a part of this specification—

Figure 1 is an end elevation of a tie embodying my invention showing the adjacent portion of a rail,

Fig. 2, a plan view of an end portion of the tie showing the portions of the rail carried thereby broken away,

Fig. 3, a side elevation of the tie end showing the rail in transverse section,

Fig. 4, a section of the tie with the removable parts absent taken on line 4—4 of Fig. 2,

Fig. 5, a similar section of the same with all the parts in place,

Fig. 6, a section on line 6—6 of Fig. 2.

Fig. 7, a section on line 7—7 of Fig. 5, a portion of the block being broken away,

Figs. 8 and 9, sections on line 8—8 of Fig. 1 and line 9—9 of Fig. 5 respectively,

Fig. 10, a section on line 10—10 of Fig. 2, and

Fig. 11, a reduced side elevation of the tie body.

Like reference characters indicate like parts throughout the views.

My tie and fastening means comprises in the present instance an oblong tubular metallic shelf or casing of rectangular cross section with open ends constituting the tie body, and consists of a base 14, sides 15, and top 16. It is preferably set on stone ballast.

Adjacent each end of the tie the walls 15 are 55 provided with oblong openings 18 disposed

opposite each other in a right hand pair and a left hand pair. Above these openings the top 16 is cut away to form a transverse recessed opening 20. Since both ends of my tie body and the securing devices for both 60 rails are identical, a description and detail showing of one end and one set of securing devices will serve for both. Beneath the outermost openings 18 at each end of the tie is a transversely disposed metallic plate 22 65 fastened to the walls 15 by rivets 23 through their angular ends 24 or otherwise. These plates 22 constitute partitions against the crushed stone which is introduced into the open outer ends of the ties. Intermediate 70 the pairs of openings near each end of the tie is a wooden block 26 provided with a lateral hole 27 to afford a finger hold to facilitate removal of the block for substitution. Each block contributes its support to 75 the rail and load.

Above the blocks, and registering in the recesses 20 are rectangular safety plates 29, each having a transversely disposed rectangular elevation 30 upon its lower face at 80 one end, and a shoulder 32 upon its upper face at the same end provided with a rectangular cavity 33. The opposite end of each plate 29 has a central rectangular recess 35. The side edges of each plate have 85 intermediate portions cut away also, forming longitudinally disposed lateral recesses 36. While the maximum width of each plate brings its edges flush with the outer surfaces of the walls 15, the recesses 36 are 90 sufficiently deep to form spaces or openings 38 between the plate and the inner surfaces of the walls 15. Through the corner margins of each of these plates are bolt holes 39. The blocks 26 are insured against longitudinal 95 movement in one direction by the elevations 30 which form abutments therefor. The shoulders 32 form abutments for the outer ends of the rail flanges.

In the drawings are shown the usual rail-way rails 41 comprising flanges 43, webs 44, and heads 45. A further abutment for the outer portion of the rail flange and a clencher or clamp therefor consists of a thick rectangular plate 47 having lateral downward 105 flanges 48 adapted to embrace the tie walls 15. This plate rests on the top 16 of the tie and is provided with corner extensions or ears 50 which with the adjacent portion of the plate overlaps the flange 43. The bottom 110

face of this plate has a cavity 51 to admit the shoulder 32, and has also a notch 52. The plate is also provided in an intermediate portion with an inclined opening 53, and is locked into position by a pair of hook bolts 55 passing through the openings 39 and through corresponding openings 56 in the plate 47 adjacent the ears 50. Each bolt 55 comprises a shank 57 passing through the 10 plates and provided with a thread 58 on its outer end to receive a nut 59 engaging the plate. Upon the lower end of shank within the tie is a lateral arm or beak 60 provided with flat oblong heads 61 registering in the 15 right hand pair of openings 18 and corresponding in shape therewith.

Inside clenchers near each end of the tie also clamp the rails. Each of these comprise a plate 62 seated in the recessed 20 opening 20. The inner margin 63 of the plate 62 is of increased thickness and is provided upon its under face with rectangular recesses 65 to receive the inner end of the plate 29. It is provided with depending 25 lateral flanges 66, and with inwardly directed ears 67 overlapping the inner margin of the rail flange 43 against which the plate 62 abuts. Intermediate the recesses 65 upon the under side of the plate 62 is a depending 30 beak or abutment 69 disposed parallel with the rail and provided with a curved forward face adapted to engage the face of the block 26. Extending outwardly from an intermediate portion of the beak and integral 35 with the plate 62 is a fin 71 having a projecting end portion 72 adapted to engage the under face of the tie top 16. The plate 62 has at its inner margin bolt holes 73 registering with two of the holes 39 and 40 through both of which pass a pair of hook bolts 74 identical in construction with bolts 55. Upon the threaded ends 76 of the bolts 74 are nuts 78 engaging the portion 63 of plate 62. And upon the ends of the bolts 45 74 are the heads or plates 80 registering in the left hand pair of the two pairs of openings 18. It will be noted that the plate 62 is easily removable.

A rail brace for the web and head of each 50 rail is provided. This consists of a hollow casting comprising an inclined top wall 82 provided with a central bolt hole 83, and having sides 84 provided in their bottom margins with recesses 85 to admit the plate 47, and in their upper forward margins with recesses 86 to receive the rail head 41. One of the walls 84 is shorter than the other for a reason to be later mentioned. A front wall 87 connecting the sides 55 engages the head. The sides, therefore, rest firmly on the tie top 16 and plate 47. The front of the sides and the front wall are held clamped against the rail by an inclined bolt 89 passing through the holes 83 and 53, and 60 whose squared head 90 registers in the cavity 65

52 of the plate 47. A nut 91 on the outer end of the bolt engages the top 82 of the brace.

When joints occur between the rails I employ an oblong plate 92 having depending 70 lips 94 upon both ends. This plate is applied to the bottom face of the rail web across the rail joint. The lips 94 are forced into the openings 38 in the adjacent ties thus being supported on and interengaging the 75 walls adjacent walls 15. The joint may be further protected by a connecting angle bar comprising a plate 96 on the web 44, a lateral extension 97, and an inturned flange 99 engaging the flange 43 and the plate 92. One 80 end of the plate 96, in the present instance extends to a point intermediate the rail brace and the rail, which is permitted by reason of the space between the web 44 and the shorter of the brace walls 84. The plate 85 96 is maintained in position by bolts 100 passing through openings 101 and 102 in the plate and web respectively and held by nuts 103.

It will be observed that the rails are 90 braced against spreading and locked against all lateral displacement, and securely held; that the parts are arranged and interengaged in such a manner as to permit quick disassemblage and replacement of parts 95. This is further facilitated by the fact that all the bolts pass comparatively loosely through all the bolt holes. It will be further noted that the wooden blocks contribute to afford a solid support for the load; and that the 100 blocks may be readily removed.

I claim,

1. In a device of the character described, a tubular metallic body comprising a base, sides, and a top, said top being provided 105 with recessed openings, supporting plates seated in the openings, and hook bolts within the body engaging the plates and sides.

2. In a device of the character described, a tubular metallic body having open ends 110 and provided with recessed openings, wooden blocks in the body below the openings, supporting plates seated in the openings and engaging the blocks, and bolts within the body connecting the plates and body. 115

3. In a device of the character described, a tubular metallic body comprising a base, sides, and a top, the top being provided with recessed openings, and the sides being provided with openings, supporting plates in 120 the recessed openings, and hook bolts comprising shanks in the plates, lateral arms within the body, and heads on the bolts registering in the said side openings.

4. In a device of the character described, 125 a tubular metallic body provided with open ends and with recessed openings in its upper portion, wooden blocks in the body below the openings, supporting plates in the openings adapted to engage the blocks, and 130

J. T. PELCHAT.
